DISC WHEELS

Heinrich Kordes, Osnabrück, Germany, assignor to
Klöckner-Georgsmarienwerke Aktiengesellschaft, Osnabrück, Germany

Filed June 21, 1956, Ser. No. 592,872

Claims priority, application Germany Dec. 19, 1955

2 Claims. (Cl. 295—11)

The present invention relates to disc wheels, more particularly for use in railway rolling stock, and provided with resilient insertions stressed principally for compression, said insertions being interposed between two outer acute-angled surfaces of a wheel rim connected with the tyre of the wheel, and the inner surfaces of a V-section annular flange connected with the wheel hub.

Various forms of construction of such wheels are known.

However, these known forms of construction enjoy little popularity in practice, chiefly because in the past it was not correctly understood how the above-named three basic elements of the wheel, namely the wheel rim, the annular flange, and the resilient insertions between them, ought to be shaped and correlated to produce a disc wheel which would combine low weight, low cost of manufacture, and optimum resilience obtained by taking advantage of the full deformation energy of the resilient insertions.

According to the invention the solution of the problem is comprised in that the wheel rim is of V-shape and that the likewise V-shaped annular flange associated with the wheel hub consists of two similar, correspondingly angled, homologous, sheet-metal rings joined together by welded dowel pins and connected with the wheel hub through welded seams and that the insertions consist of a castable elastic synthetic plastic material.

For making the insertions it is preferred to use a synthetic plastic or rubber-like material consisting of softened polyurethane, for instance the product commercially known by the trade name of "Vulkollan" which is a synthetic material that stands up well to cyclic deformation, excels by its anti-abrasive properties and fatigue resistance, besides being unaffected by petrol and oil, and has a low specific weight which in conjunction with a hollow-section wheel rim enables the total weight of the wheel to be sensibly reduced.

The employment of the above mentioned rubber-like synthetic plastic material affords the further advantage that the insertions may be bonded to the metal of the wheel rim by moulding them on to the rim, and the connection between the insertions and the sheet-metal apertured discs may conveniently be effected by means of a suitable cement. This procedure avoids the loss of time, the complications, and the difficulties of control involved in the hitherto customary method of vulcanising the insertions in position, a necessity that could not be avoided when employing the natural or synthetic rubbers hitherto used. Moreover, in view of the unusually high fatigue resistance to cyclic flexural deformation possessed by the said rubber-like plastic materials, pre-compression of the insertions can be greatly diminished without reducing their life and this in turn produces an exceptionally high radial and axial resilience in a disc wheel constructed according to the present invention. It is also a matter of importance that

the elastic qualities of the said synthetic plastics can be controlled within very wide limits by the addition of plasticisers and other compounding materials so that they can be adapted specifically to the loads they are designed to withstand.

The invention will be hereinafter more particularly described with reference to the accompanying drawings which show an illustrative example of a disc wheel according to the invention.

10 In the drawings:

Fig. 1 is a cross-section through a portion of the body of the wheel with the tyre shrunk on;

Fig. 2 is a partial section of a similar wheel including an earthing cable;

15 Fig. 3 is a side elevation of the wheel shown in Fig. 1;

Fig. 4 is a section taken along the line E—F of Fig. 1, and

Fig. 5 is a section taken along the line C—D of Fig. 2.

As will be seen more particularly by reference to the sections shown in Figs. 1 and 2 the disc wheel according to the invention comprises a wheel hub 1, the disc proper which in the present instance comprises mainly sheet metal apertured discs 2, 3 combined to form an annular flange, rubber-like insertions 4, 4', and, finally,

20 25 a V-shaped wheel rim 5 with shrunk on tyre 8. The hub 1 is preferably a drop-forging. The two sheet discs 2, 3, as will be readily understood from Figs. 1 and 2, are two identical parts, a factor which keeps down the cost of production and storage. The two sheet-metal discs 2, 3 are joined together by dowels 7 fixed in position by welds 7' after the insertions 4, 4' have been slightly precompressed. The hub 1 and the annular flange are joined by seam welding along 1a and 1b, the welded joint also holding the two metal discs 2, 3 of

30 35 the flange together. The insertions 4, 4' are preferred to be ring-shaped bodies made of a rubber-like mouldable synthetic plastic material, and preferably a plastic belonging to the group Desmodur/Desmophen, known in the trade under the name of "Vulkollan."

35 40 In view of the comparatively low pre-compression to which the insertions need be subjected if they consist of the above specified plastic they form resilient cushions capable of storing an unusual amount of elastic deformational energy both in the radial as well as in the axial direction. Unlike rubber, these insertions need

45 50 not be subjected to high axial pre-compression, as is the case with rubber to enable it reliably to absorb the loads that occur in operational service, although the rubber is thereby deprived of the major proportion of its elastic potential.

Practical tests have proved that pre-compression between 6.8 to 8 tons is sufficient for the wheels according to the invention whereas rubber-cushioned wheels with a T-shaped ring and disc-shaped rubber insertions

55 60 require, for instance a pre-compression of from 24 to 60 tons.

To balance and centre the wheel body on a lathe when machining the tyre, the wheel rim 5 is provided with three radially inwardly directed and angularly spaced lugs 6 the shape of which can be seen more particularly in Fig. 4. A hole 6' is drilled through each of the lugs, and corresponding holes 2a and 2b which align with the holes 6' are provided in the sheet metal discs,

65 70 as shown in Fig. 1. By inserting a threaded bolt or the like through these holes the wheel rim 5 and the portions 2, 3 of the annular flange can be directly connected together and the cushioning members 4 and 4' bridged.

Electrical connection between the parts 5 and 2, 3 is effected by means of an earthing cable 9 (Figure 2) secured by screws 10 and 10' to the annular flange 2 and the wheel rim 5 respectively in electrical contact

therewith. As will be seen, the earthing cable is disposed inside the wheel structure so that it is well protected from external interference and possible damage.

The insertions 4, 4' are mounted in the first instance preferably by moulding the rubber-like synthetic plastic material on to the wheel rim 5 and will then allow the plastic rings, i.e. the insertions, to be simultaneously moulded on to the sheet metal discs 2, 3. If the wheel rim 5 is of unit construction, the sheet-metal discs 2, 3 must be bonded to the insertions in a second operation by means of a suitable cement which provides a bond with the metal. The insertions are then pre-compressed to the low pressure required. Finally, the pre-compressed insertions are secured by inserting the dowels 7 in the discs 2, 3 and welding.

I claim:

1. A disc wheel for railway rolling stock comprising a wheel hub, a V-shaped annular flange surrounding said hub co-axially therewith and spaced therefrom, discs rigidly supporting the annular flange on the hub, a V-shaped wheel rim surrounding the annular flange co-axially therewith and radially spaced therefrom, a tyre supported by said rim, pre-compressed resilient insertions of a mouldable elastic synthetic plastic material interposed between the wheel rim and the flange in engagement respectively therewith, inwardly directed angularly spaced lugs on said wheel rim with an aperture extending through each of said lugs, and apertures in said annular flange and axially aligned with the lug apertures to permit the insertion of bolts or the like through the axially aligned apertures to connect directly together

the wheel rim and the annular flange and thereby temporarily to bridge the resilient insertions when the wheel is mounted on a lathe for machining the tyre of the wheel.

- 5 2. A disc wheel for railway rolling stock comprising a wheel hub, a V-shaped annular flange surrounding said hub coaxially therewith and spaced therefrom, discs rigidly supporting the annular flange on the hub, a V-shaped wheel rim surrounding the annular flange coaxially therewith and radially spaced therefrom, a tire supported by said rim, pre-compressed resilient insertions of a moldable elastic synthetic plastic material interposed between the wheel rim and the flange in engagement respectively therewith, and inwardly spaced lugs on said wheel rim each with an aperture therethrough, said annular flange having apertures therethrough in alignment with the lug apertures to permit the insertion of means through the aligned apertures to directly secure the wheel rim and the annular flange together when the tire requires machining.
